UNITED STATES PATENT OFFICE

EUGENE F. MILTENBERGER, OF RED BANK, NEW JERSEY, ASSIGNOR TO EASTERN CORPORATION, OF NEW YORK, N. Y., A CORPORATION OF DELAWARE

MOLD CARRYING CONVEYER

Application filed February 1, 1930. Serial No. 425,156.

In foundries it is common practice to make the molds in one department or section of the plant and carry them to another department or section where the castings are poured. Of course, this does not apply where the casting to be made are exceptionally large, but does apply where the molds are readily transportable.

It has been proposed to move the molds along roller conveyors, but so far as I am aware this has not heretofore been entirely successful due in part to the fact that the slight jarring of the mold in moving along the conveyors over the rollers often loosens some of the sand forming the mold so that the resulting casting is defective.

If the rollers of the conveyer be sufficiently long to support the mold across substantially its entire width the conveyer itself becomes a source of annoyance because it is difficult for the workman to step across it in going from one point to another in the plant.

The main object of the invention is to secure mobile storage by providing a conveyer mechanism over which the sand molds may be conveyed with the minimum amount of jarring or shaking action and which interferes to the minimum extent with the movement of the workman about the plant.

As one important feature of my invention I provide a pair of comparatively narrow roller conveyers over which a workman may readily step and I carry the molds upon resilient platforms which bridge across both conveyers and are supported by both so that the jarring effect is minimized by the resiliency of the platform.

Any jarring effect caused by the movement of the platform over one set of rollers is in part neutralized by the simultaneous partial supporting of the platform on the other set of rollers as well as the resiliency of the platform.

A plurality of molds may be placed on a single platform and the platform may be easily moved along the conveyers by a single workman walking between the two conveyers.

Thus my apparatus interferes to the mini-

mum extent with the free use of the floor space, reduces to the minimum the shaking loose of sand in the molds, and permits one workman to easily move a plurality of the molds to the point at which it is desired to pour the castings.

In the accompanying drawings there is illustrated merely one embodiment of the invention.

In these drawings:

Fig. 1 is a top plan view,

Fig. 2 is a transverse section on the line 2—2 of Fig. 1, and

Fig. 3 is a perspective view showing the under side of the platform.

In the form illustrated there are a pair of roller conveyors each including a plurality of comparatively short rollers 10 with their axes or pintles mounted in angle irons 11 carried by a suitable base. The height of the rollers and the width of the supporting base 12 is such that a workman may easily step over and the two roller conveyers are mounted parallel and at such distance apart that a workman may walk along between them. In connection with these roller conveyers I employ a resilient platform 13 which is advantageously made of comparatively thin wooden board and which is adapted to bridge across and rest upon the two roller conveyers. This platform includes a top or body portion with metal runners 14 upon the under side. These runners or battens are preferably formed of sheet metal and are spaced apart to the same distance as are the roller conveyers and extend transversely of the body of the platform. These each include a flat wall 15 with substantially narrow side walls 16 spacing the wall 15 from the body of the platform. At the edges of the side walls 16 flanges 17 may be secured to the body of the platform in any suitable manner as for instance by bolts or screws.

The guideways are thus substantially channel shaped and serve as a reinforcement transversely of the platform to stiffen it in one direction, but they are not connected together and thus there is no stiffening or reinforcement of the platform between the roller conveyers. The guideways

14 bridge across a plurality of the rollers and provide a metal surface for moving upon the rollers so that in case any one roller is slightly higher or lower than the rest there is the minimum jar or shaking effect as the platform passes over it and the resiliency of the platform further cushions any such jar.

5 If only one or a few molds are carried on the platform they may be spaced midway 10 between the two conveyors so that they have the full effect of the resiliency of the platform. If a large number of molds are carried on the platform they may be arranged 15 along the full length of the platform as indicated by the reference character A in Fig. 2. With this arrangement all of the molds get the benefit of the resiliency of the platform.

Having thus described by invention, what 20 I claim as new and desire to secure by Letters Patent is:

1. A conveyer including a pair of spaced supports, a pair of angle irons upon each support, a series of rollers carried by each 25 pair of angle irons, and a platform having metal runners extending transversely thereof upon the under surface and adapted for engagement with said rollers to support said platform and facilitate the movement of the latter over said rollers, said runners being 30 substantially channel shaped in cross-section and reinforcing the platform in the direction of the length of said series of rollers.

2. A mold carrying conveyer for use in 35 foundries, including a pair of stationary substantially parallel roller supports, each having a series of conveying rollers, said supports being spaced apart to form a passageway therebetween along which a work- 40 man may walk, and a resilient platform bridging across and supported by both series of rollers, the rollers and platform being at such height above the floor that the workmen walking between the two series of rollers 45 may push said platform over the rollers without unduly bending over, and the length of the rollers and the height thereof being such that the workmen may conveniently step over the rollers to the open space between the two series.

50 3. A mold carrying conveyer for use in foundries, including a pair of stationary substantially parallel roller supports, each having a series of conveying rollers, said 55 supports being spaced apart to form a passageway therebetween along which a workman may walk, and a platform bridging across and supported by both series of rollers, the rollers and platform being at such height above the floor that the workmen 60 walking between the two series of rollers may push said platform over the rollers without unduly bending over, and the length of the rollers and the height thereof being such that the workmen may conveniently 65 step over the rollers to the open

space between the two series, and said platform being of a width at least equal to three times the diameter of a roller, whereby the weight of the platform and the load carried thereby is distributed over a plurality of rollers, and said platform having reinforcing strips upon the under surface thereof and extending transversely thereof for engagement with said rollers.

4. A conveyer including a pair of spaced supports, a pair of angle irons upon each support, a series of rollers carried by each pair of angle irons, and a platform having metal runners extending transversely thereof upon the under surface and adapted for engagement with said rollers to support said platform and facilitate the movement of the latter over said rollers, said runners reinforcing the platform in the direction of the length of said series of rollers.

Signed at New York, in the county of New York and State of New York, this 29th day of January, A. D. 1930.

EUGENE F. MILTENBERGER.
